Primary Examiner—Jeffrey D. Asch

(74) Attorney, Agent, or Firm—Morgan & Finnegan LLP;
Mark J. Abate, Esq.(57) **CLAIM**

I claim the ornamental design for a cellular telephone, as shown and described.

DESCRIPTION

FIG. 1 is a front view of a cellular telephone embodying the claimed design;

FIG. 2 is a top view thereof;

FIG. 3 is a side view thereof, with the opposite side being a mirror image;

FIG. 4 is a back view thereof; and,

FIG. 5 is a bottom view thereof.
